UNITED STATES PATENT OFFICE.

WILLIAM D. THOMPSON, OF DETROIT, MICHIGAN, ASSIGNOR TO HUTCHINS CAR ROOFING COMPANY, OF DETROIT, MICHIGAN, A CORPORATION OF MICHIGAN.

CAR-ROOF.

1,025,031.

Specification of Letters Patent. Patented Apr. 30, 1912.

Application filed June 11, 1909. Serial No. 501,612.

To all whom it may concern:

Be it known that I, WILLIAM D. THOMPSON, a citizen of the United States of America, residing at Detroit, in the county 5 of Wayne and State of Michigan, have invented certain new and useful Improvements in Car-Roofs, of which the following is a specification, reference being had therein to the accompanying drawings.

10 The invention relates particularly to an all-metal freight car roof wherein the roofing boards are entirely dispensed with, and it consists in the novel and simple construction of the roof, in the peculiar arrangement and combination of parts, and in various details of construction as will be more fully hereinafter set forth.

15 The single figure illustrating my invention is a perspective view of the car roof, with some of the parts in section and some broken away to more fully illustrate the construction.

20 The reference-letter A designates a sub-structure upon which the metal roofing or covering is supported. It is composed of the usual wooden purlins B and trough-shaped metallic carlines C. In this instance I have shown the latter as extending entirely across the roof from eave to eave, this 25 being the preferable form. At their lower ends the carlines are provided with depending flanges or plates D that are adapted to be secured in any suitable manner to the car side or plate.

25 Arranged preferably upon each side of the several carlines is a series of supporting strips E, extending transversely as shown beside the carline and adapted to form a lateral extension therefor to receive 30 and support the edge of the metallic sheet. The strips are preferably of wood and two in number for each series, and the two strips are adapted to lie flush with the tops of the purlins and are spaced one from another so 35 as to leave an unbroken portion or section of the wooden purlin intermediate their ends. Recesses, as a, are formed in the top portions of each purlin, as shown, in which the ends of the strips rest, the recesses being of 40 a depth to bring the top of the supporting strip flush with the top of the purlin strip, as above pointed out. The unbroken portion of the purlin intermediate the strip 45 ends is designated by the reference-letter b.

This method of construction, while permitting the strips to lie flush in the desired manner, does not seriously weaken the purlins. 55

5 F represents the metallic sheets, arranged in longitudinal series edge to edge upon the purlins, each sheet overlapping at its side edge the series of supporting strips adjoining the carline. The side edges of the sheets are provided preferably with upstanding flanges G designed to abut against the upstanding flange or flanges upon the carline, and H represents a plurality of transversely arranged cap plates extending over the carline and sheet flanges at their side edges inclosing the joint. The cap plates are 60 preferably provided with lateral flanges I that when the caps are in place rest upon the sheet bodies, as plainly indicated. At the sheet ends adjoining the ridge, upstanding flanges J are provided similar to the 65 side flanges described. These are covered by suitable ridge plates, as K, conforming in configuration substantially to the caps I. Any suitable cap, as L, may be employed to cover the joint at the intersection of the 70 plates at the ridge. The metallic sheets terminate at their lower ends in downwardly turned flanges M adapted to be secured to the car side, and the caps I in similar flanges O also adapted to be secured to the car side 75 and projecting preferably below the plate flanges, as indicated.

What I claim as my invention is,—

1. In a car roof, a substructure comprising purlins and trough-shaped carlines, of 80 supporting strips independent and arranged upon opposite sides of each carline, forming lateral extensions therefor, the strips being arranged in a number of transverse series upon the purlins and flush with their 85 tops, and roofing plates upon the purlins overlapping at their side edges the supporting strips.

2. In a car roof, the combination with a series of wooden purlins, of a metallic 90 trough-shaped carline, a plurality of wooden supporting strips extending transversely of the purlins beside the carline, and lying flush with the purlin tops, the strip ends resting within recesses formed within 95 the purlins, and the recesses for adjoining strip ends being spaced, leaving unbroken 100 portions of the purlins intermediate the 105

strips, and a roofing sheet overlapping at its side edge the supporting strips.

3. In a car roof, the combination with a sub-structure comprising purlins and carlines formed with upstanding flanges thereon, of supporting strips independent of and adjoining the carlines forming lateral extensions therefor, and roofing plates upon the purlins overlapping at their side edges 10 the supporting strips.

4. In a car roof, the combination with a substructure comprising purlins and carlines, of independent supporting strips arranged adjacent the carlines and having 15 their upper faces in the plane of the upper

face of the purlin, and roofing plates resting upon said purlins and said strips.

5. In a car roof, the combination with the carlines and the purlins, of supporting strips extending between the purlins independent of and adjoining the carlines, and roofing plates resting upon the supporting strips. 20

In testimony whereof I affix my signature in presence of two witnesses.

WILLIAM D. THOMPSON.
